(57) **CLAIM**

(22) Filed: **Dec. 7, 2005**

The ornamental design for a cable connector assembly, as shown.

(30) **Foreign Application Priority Data**

DESCRIPTION

Jun. 7, 2005 (CN) 2005 3 0084731

FIG. 1 is a front, top and right side perspective view of a cable connector assembly showing the first embodiment of my new design;

(51) **LOC (8) Cl.** **13-03**

FIG. 2 is a front elevational view thereof;

(52) **U.S. Cl.** **D13/147**

FIG. 3 is a rear elevational view thereof;

(58) **Field of Classification Search** D13/133,

FIG. 4 is a left side elevational view thereof;

D13/146–147, 154, 184, 199; 439/352–353,

FIG. 5 is a right side elevational view thereof;

439/357–358, 677–681, 607, 610, 686

FIG. 6 is a top plan view thereof;

See application file for complete search history.

FIG. 7 is a bottom plan view thereof;

(56) **References Cited**

FIG. 8 is a front, top and right side perspective view of a cable connector assembly showing the second embodiment of my new design;
